EDWARD J. KEARNEY, OF WAUWATOSA, AND THEODORE TRECKER, OF WEST ALLIS, WISCONSIN, ASSIGNORS TO KEARNEY AND TRECKER COMPANY, OF MILWAUKEE, WISCONSIN, A CORPORATION OF WISCONSIN.

MEANS FOR LUBRICATING MACHINE-TOOLS.

No. 834,063.

Specification of Letters Patent.

Patented Oct. 23, 1906.

Application filed February 8, 1905. Serial No. 244,333.

To all whom it may concern:

Be it known that we, EDWARD J. KEARNEY, residing at Wauwatosa, and THEODORE TRECKER, residing at West Allis, in the county of Milwaukee and State of Wisconsin, citizens of the United States, have invented a certain new and useful Means for Lubricating Machine-Tools, of which the following is a specification, reference being had to the accompanying drawing, forming a part hereof.

The main object of this invention is to provide for and insure thorough lubrication of the power-transmitting gearing of machine-tools, such as milling-machines, without attention and care on the part of the operator.

It consists in certain novel features of construction and in the peculiar arrangement and combinations of parts, as hereinafter particularly described and claimed.

The accompanying drawing shows a vertical section of a milling-machine embodying the invention.

a designates a box-frame or hollow case like or similar to those usually employed in this class of machines. It is formed or provided with boxes or bearings *b*, *c*, *d*, and *e* for a train of power-transmitting and speed-changing gearing, and in the lower part thereof an oil well or receptacle *f* is formed. The boxes *b*, *c*, and *e* are formed or provided with external pockets, cups, or receptacles *g*, which communicate, through openings or passages, with the interior bearings and are adapted to catch oil falling or flowing from above and deliver it to the journals of the gearing.

The train of gearing, which is inclosed in the frame or housing *a* and comprises a number of horizontal shafts arranged one above another and connected by intermeshing gears, is vertically disposed or so arranged that the oil will flow by gravity from the upper to the lower gears and bearings and thence back into the well or reservoir below. The outer end of the long bearing *e* is formed with an annular oil-intercepting channel, which communicates on the under side, through a passage or opening *h*, with the interior of the hollow bracket surrounding said bearing and thence with the interior of the casing *a*.

i is a pump having an actuating connection with a part of the gear-train and a suction-

pipe *j* extending down into the well or reservoir. It is connected by an upwardly-extending discharge-pipe *k* with a horizontal perforated pipe or distributing-head *l*, arranged over the upper gears of the train in position to discharge oil thereon and into the pockets or receptacles *g* of the upper bearings *b*.

In the present case for the purpose of illustration a rotary pump is shown connected directly by a pinion with the lower gear of the power-transmitting train; but any other form of pump suitable for elevating the oil from the well or reservoir to the upper part of the train of gearing may be used.

In the machine shown in the drawing the tool-arbor or work-spindle *m* is provided with a number of change-speed gears of different diameters arranged to be engaged by either one of a like number of corresponding gears shiftable lengthwise upon the shaft *n* below and parallel with said arbor or spindle.

o is the driving-shaft, provided with a pulley *p* and a gear *q*, which is connected by an intermediate gear *r* and a pinion *s* with the shaft *n*.

An auxiliary train of change-speed gearing *t* for operating the sliding work table or platen (indicated by dotted lines on the drawing) is actuated through the intermediate gear *r* of the work-spindle driving-train and is inclosed in a housing *u*, formed on or attached to the main frame. This auxiliary train of gearing is supplied with oil from a pocket or receptacle *g'*, located within the main frame or casing *a* below the adjacent bearing *c* and communicating, through an opening or passage, with the interior of the housing *u*. An overflow opening or passage *v*, located above the lower sides of the gears of this auxiliary train, conducts the surplus oil back into the main frame or casing, where it runs down into the pocket or receptacle *g*, which supplies the driving-shaft *o*. The construction and arrangement of the component parts of the power-transmitting and change-speed gearing in milling-machines and other machine-tools may, however, be varied within wide limits without materially affecting the principle and operation of our lubricating system and without departing from the spirit and intended scope of our invention.

When the machine is in operation, the pump *i* draws oil from the well or reservoir *f* through the pipe *j* and forces it up through the pipe *k* into the perforated pipe *l*, which distributes and discharges it in small streams upon the upper gears of the train and into the pockets or receptacles *g* of the boxes *b*, as well as upon the arbor or spindle *m* and to some extent upon the gearing below. The surplus oil delivered to the journals of the arbor or spindle *m* finds its way out through the inner ends of the boxes or bearings *b* and following down the walls of the casing *a* is caught in the pockets *g* of the boxes *c* and conducted to the journals of the shaft *n*. From the inner ends of the boxes *c* the surplus oil escapes and follows down the walls of the casing into the reservoir *f* on one side of the machine and on the other side into the pocket or receptacle *t*, from which it runs into the housing *u*, in which it rises to the level of the overflow-opening *v*. The excess of oil supplied to said housing that is not required for the lubrication of the gearing therein is discharged through the opening *u* back into the casing *a* and flows down the wall thereof into the pocket or receptacle *g*. The surplus oil supplied to the shaft *o* in the bearing *e* escaping into the annular channel in the outer end of said bearing flows back through the passage or opening *h* into the well or receptacle *f*. The entire train of gears and their journal-bearings are thus copiously supplied with oil without care or attention on the part of the operator, the surplus oil flowing back into the well or reservoir *f*, from which it is again elevated by the pump and delivered to the upper part of the gear-train.

The box or bearing of any arbor, spindle, or shaft of the train which projects through the casing may, like the box *e*, be provided at its outer end with an oil-intercepting channel communicating through a drain opening or passage on the under side with the interior of the casing. In short, the construction and arrangement of the several parts of the lubricating system may be varied to adapt it to different machine-tools and different conditions within the scope of our invention without affecting its principle or mode of operation.

We claim—

1. In a means for lubricating machine-tools the combination with a train of power-transmitting gearing comprising a number of horizontal shafts arranged one above another and connected by intermeshing gears, of a frame or case containing said gearing, an oil-reservoir located below said gearing, and a pump adapted to elevate oil from said reservoir and distribute and deliver it to upper gears of said train, substantially as described.
2. In a means for lubricating machine-tools the combination with a train of power-trans-

mitting gearing comprising a number of horizontal shafts located one above another, of a frame or case containing said gearing and provided with boxes having oil-cups communicating with the journal-bearings of said shafts, an oil-reservoir located below said gearing, and a pump adapted to elevate oil from said reservoir and to distribute and deliver it into the oil-cups of the upper bearings from which it flows by gravity into those below and thence back into said reservoir, substantially as described.

3. In a means for lubricating machine-tools the combination with a train of power-transmitting gearing comprising a number of horizontal shafts arranged one above another and connected by intermeshing gears, of a frame or case containing said gearing and provided with boxes having oil-cups communicating with the journal-bearings of said shafts, an oil-reservoir located below said gearing, and a pump adapted to elevate oil from said reservoir and to distribute and deliver it to the upper gears and into the oil-cups of the upper bearings from which it flows by gravity into those below and thence back into said reservoir, substantially as described.

4. In a means for lubricating machine-tools the combination with a train of power-transmitting gearing comprising a number of horizontal shafts arranged one above another and connected by intermeshing gears, of a frame or case containing said gearing, an oil-reservoir located below said gearing, a distributing-head arranged to deliver oil to the upper gears of said train, and a pump adapted to supply oil from said reservoir to said head, substantially as described.

5. In a means for lubricating machine-tools the combination with a train of power-transmitting gearing comprising a number of horizontal shafts located one above another, of a frame or case containing said gearing and provided with boxes having oil-cups communicating with the journal-bearings of said shafts, an oil-reservoir located below said gearing, a distributing-head arranged to deliver oil to the upper gears and to the oil-cups of the upper bearings from which it flows by gravity into those below and thence back into said reservoir, and a pump adapted to supply oil from said reservoir to said head, substantially as described.

6. In a means for lubricating machine-tools the combination with a train of power-transmitting gearing comprising a number of horizontal shafts arranged one above another and connected by intermeshing gears, of a frame or case containing said gearing and provided with boxes having oil-cups communicating with the journal-bearings of said shafts, an oil-reservoir located below said gearing, a distributing-head adapted to deliver oil to the upper gears and to the oil-cups of the upper bearings from which it flows by gravity into

- those below and thence back into said reservoir, and a pump adapted to supply oil from said reservoir to said head, substantially as described.
- 5 7. In a means for lubricating machine-tools the combination with a train of power-transmitting gearing, comprising a number of horizontal shafts arranged one above another and connected by intermeshing gears, of a frame or case having bearings therefor, an oil well or reservoir in the lower part of the machine, an auxiliary gear-train contained in a housing which is adapted to hold oil in contact with gears of said train and communicates with a pocket or receptacle within the main frame or case below the upper part of the main train of gearing, and a pump arranged to elevate oil from said well or reservoir to the upper part of the main train, substantially as described.
- 15

8. In a means for lubricating machine-tools, the combination with a power-transmitting train of gearing, of a frame or case having bearings for said gearing with pockets for catching oil, an oil well or reservoir below said train, a perforated pipe located over and arranged to discharge oil upon the upper part of the train and into the pockets of the upper bearings, and a pump arranged to elevate oil from said well or reservoir into said pipe, substantially as described.

In witness whereof we hereto affix our signatures in presence of two witnesses.

EDWARD J. KEARNEY.
THEODORE TRECKER.
